P. A. HUDDLESTON,
ELECTRIC ILLUMINATING ALARM CLOCK,
APPLICATION FILED NOV. 10, 1913.

1,133,562.

Patented Mar. 30, 1915.

UNITED STATES PATENT OFFICE.

PLEASANT A. HUDDLESTON, OF OKLAHOMA, OKLAHOMA.

ELECTRIC ILLUMINATING ALARM-CLOCK.

1,133,562.

Specification of Letters Patent. Patented Mar. 30, 1915.

Application filed November 10, 1913. Serial No. 800,186.

To all whom it may concern:

Be it known that I, PLEASANT A. HUDDLESTON, a citizen of the United States, residing at Oklahoma, in the county of Oklahoma and State of Oklahoma, have invented certain new and useful Improvements in Electric Illuminating Alarm-Clocks, of which the following is a specification.

My invention relates to electric alarm and lighting attachments to be used in connection with clocks having a time alarm.

One of the objects of my invention is to provide mechanism for actuating an electric bell and lighting an electric lamp at will or at a predetermined time.

Another object is to provide means by which the electric bell may be put out of circuit and silenced, while the electric lamp remains lighted; or the lamp may be lighted at will or at a predetermined time.

I arrange the apparatus so that it may be connected by means of the usual flexible twin conductor cord and attachment plug to a wall socket connected to the electric lighting circuit; or in case there is no available lighting circuit, the operating current may preferably be supplied by a set of batteries preferably inclosed within the apparatus.

In the accompanying drawings, Figure 1 is an end elevation of an apparatus embodying my invention and showing in dotted lines the manner of attaching an ordinary form of alarm clock; Fig. 2 is a longitudinal section thereof; Fig. 3 is a detail top plan view of the clock-actuated trigger and switch-arm; Fig. 4, is a diagram of the electric circuits showing the apparatus connected to a house electric lighting circuit; and Fig. 5 is a diagram showing the circuits within the apparatus when operated by batteries.

A casing, 1, which may be constructed of metal, wood or other suitable material, is provided with a lamp socket 2, and electric pilot lamp 3, of low voltage, preferably 3 or 4 volts.

An electric alarm 4, is secured within the casing, the bell 5 extending through the wall, and a set of battery cells 6 may also be inclosed.

To one end of the casing is secured a skeleton frame having upright posts or standards 7, 7^a connected by a cross-bar 8. Spring clips 9, may be secured to the standards to engage the sides of the clock 10 and maintain it in proper position. The upper

end of the standard 7 terminates in a horizontal arm which carries the trigger and switch mechanism to be actuated by the striking hammer 12 of the alarm clock. The switch-arm 14 of the trigger mechanism is pivotally mounted on the arm 7' and is provided with a tooth 15, adapted to be engaged by the dog 16, of the trigger 18. When the hammer 12 of the alarm clock is actuated, striking the trigger 18, the switch-arm 14 is disengaged and is snapped by the spring 13, against the insulated contact plate and stud 14^a, thereby closing the circuit between the wires 32 and 33.

The alarm clock may be of the ordinary type and may be slipped in the direction of the arrow in Fig. 2, into position between the spring clips 7, 7^a, the back of the clock bearing against the cross-bar 8.

When my apparatus is to be used in connection with the electric lighting circuit of a house, I prefer to connect a wall-plug 29 to the contacts of the room switch 25 in the manner indicated in Figs. 1 and 4, so that the alarm apparatus may be conveniently connected by means of a flexible electric cord connection.

One contact of the room lamp switch 25, usually of the snap-switch type, is connected to one of the mains 27, the room lamp 28 being connected to the other main and to the other switch contact. The wall-socket 29 is also connected to the contacts of the room switch. The alarm apparatus is provided with plug contacts 30, which can be placed in circuit with the lighting mains by means of a flexible cord conductor 32 connecting the plug contacts with the wall-socket 29. The circuits will be readily understood from Fig. 1 and the diagram, Fig. 4.

The operation will be apparent to those skilled in the art from the above description of the apparatus. Assuming that the apparatus has been connected to a wall plug 29, by means of a flexible connector cord 32, and the alarm of the clock has been set with the alarm hammer 12 in position to strike the trigger 18. Also that the contacts of the room-switch 25 and clock switch 14, are in the open position, as indicated in Fig. 4. At the instant the alarm is actuated at the hour previously set, the hammer 12 strikes the trigger 18, releasing the clock switch arm 14, which is thereupon swung around by spring 13, into engagement with the con-

tact 14^a, thereby completing the circuit from the mains 27, and causing the electric bell 4 to ring and lighting the room lamp 28 and pilot lamp 3. This will arouse the occupant 5 of the room, who will close the room switch 25, thereby short-circuiting the bell and pilot lamp but leaving the room lamp 28 lighted.

If it is desired to use my apparatus in a 10 room which is not provided with electric lighting or it is not convenient to connect a wall socket to the mains, my apparatus can be operated by means of the battery cells 6, which may be carried within the casing 1. 15 With the circuits arranged as shown in Fig. 4, the battery switch 35 is closed and the alarm on the clock is set as previously described. When the alarm is actuated at the predetermined hour, the switch 14 is closed 20 in the manner described, thereby closing the battery circuit through the electric bell 4 and pilot lamp. The occupant of the room, upon being aroused can close the bell switch 37, thereby short-circuiting and silencing the 25 bell, while leaving the lamp 3 lighted, and he may leave the lamp lighted or turn it out at pleasure.

It will be understood that in the arrangement shown in Figs. 1 and 4, either the room 30 lamp or the pilot lamp, or both, may be lighted whenever desired by closing the proper switches, independent of the alarm. When the apparatus is operated by the battery cells, the circuits may be connected as 35 shown in the modified arrangement illustrated diagrammatically in Fig. 5.

My alarm and lighting apparatus is exceedingly compact and may be conveniently carried in a satchel. The parts are adapted 40 to be used in combination with the ordinary alarm clock and it is, of course, understood that the skeleton frame may be made telescopic or adjustable so as to adapt it to varying sizes of clocks, and may also be detachably connected to the case or be made to fold down upon the case when not in use. I have described the construction illustrated 45 in the drawings in detail for the purpose of disclosing an embodiment of my invention but it is to be understood that various changes can be made therein by those skilled in this art without departing from the spirit 50

of my invention. Thus, for illustration, the switch arm 14 might be closed directly by the blow of the hammer 12, instead of being 55 spring-actuated, and dispensing with the trigger, and other obvious changes may be made.

I claim:—

1. Alarm mechanism comprising a clock 60 provided with a striking hammer, an electrically operated alarm, circuit connections leading from said alarm to a source of electric current, a casing having a standard or frame, a spring-actuated switch secured 65 thereto and connected in circuit with said alarm, and a trigger carried by said frame adjacent said hammer and adapted to hold said switch in open position against the tension of said spring until released by said 70 hammer.

2. Alarm mechanism comprising a clock 75 provided with a striking hammer, an electrically operated alarm, circuit connections leading from said alarm to a source of electric current, a casing having a standard or frame, a spring-actuated switch secured thereto and connected in circuit with said alarm, a trigger carried by said frame adjacent said hammer and adapted to hold 80 said switch in open position until released by said hammer, and means for short-circuiting said alarm at will, thereby permitting the lamp to remain in circuit.

3. The combination with a clock having a 85 striking member adapted to be automatically operated at a predetermined time, of a casing having a frame provided with means to receive and clamp the clock, switch mechanism carried by the casing and located adjacent said striking member, a source of 90 electric currents, a plurality of electrically energized devices, conductors connecting said switch mechanism with said electrically energized devices, and means for short-circuiting 95 one of said devices while leaving the other device in circuit with said source.

In testimony whereof I affix my signature in presence of two witnesses.

PLEASANT A. HUDDLESTON.

Witnesses:
